COOLING SYSTEM

Courtenay D. Marshall and Carroll O. Buttrill,
Beaumont, Tex., assignors to Socony-Vacuum
Oil Company, Incorporated, New York, N. Y., a
corporation of New York

Application October 3, 1941, Serial No. 413,428

7 Claims. (Cl. 62—170)

This invention has to do with the art of cooling and is particularly concerned with the operation of multiple pass direct refrigeration chillers for the chilling of solvent-oil-wax mixtures utilized in the process of dewaxing petroleum fractions, although the difficulties met therein and the solution of those difficulties is applicable to numerous other systems of related type.

While the invention herein disclosed will be discussed in its relationship to the chilling of solvent-oil-wax mixtures and the apparatus used therein, this narrowing of the discussion is for convenience and for purposes of exemplification, and not by way of limitation.

In the chilling of solvent-oil-wax mixtures, hereinafter spoken of as oil, the oil is passed through a series of tubes, usually horizontally arranged, in each of which tubes there is a helical rotating scraper to remove material, deposited from the oil by cooling, from the internal tube wall. Each of these pipes or tubes is surrounded by a jacket and an operating unit or chiller comprises several runs of such horizontal tubes. For light cooling duty, chilled brine is circulated through the jackets. For more severe duty, what is usually termed a direct expansion ammonia system is used. This invention is concerned with this phase and is applicable not only to systems using ammonia but to a system using any liquid refrigerant wherein a portion of the liquid refrigerant is vaporized to cool the remainder, and the remaining liquid so cooled, is then circulated in indirect heat exchange relationship with the material to be cooled.

In chillers as at present operated, there is a separate ammonia expansion tank for each group of horizontal tubes constituting a single chiller, and from this tank the liquid ammonia is led by gravity into the annular jacket surrounding each of the several tubes. Even under very low-load operating conditions some of the liquid ammonia further evaporates in this annular space, and under high load conditions, as usually encountered, this becomes pronounced. As a result, the annular space is occupied not by liquid but by a boiling liquid containing gas bubbles and in the upper portion by gas. This condition reduces the heat transfer capability of the unit. Due to this, such equipment has a very definite load capacity below what would normally be expected under conditions of liquid film heat transfer upon both sides of the heat transfer wall.

This invention has for its object the provision of process and apparatus whereby high heat transfer conditions may be maintained uniformly

throughout such a direct expansion refrigeration system, whereby changes in loading rate may be met by a flexible distribution of coolant, and whereby increases in loading will not of themselves create a condition preventing the refrigerant from properly responding to the increased loading.

In order to understand this invention reference is now made to the drawing attached hereto. 10 This drawing shows the process of the invention and apparatus appropriate thereto in diagram form.

In this drawing, jacketed chilling tubes 1, 2, 3, 15 4 constitute a chilling unit, 5, and tubes 6, 7, 8, 9 constitute a second such unit 10. Cooling fluid therefor, being the unvaporized portion of the refrigerating medium which has been cooled by its own partial vaporization, is held in storage in expansion drum 11. This cooling fluid is withdrawn from drum 11 by pump 12 and supplied under pressure to cold fluid header 13, from which pipe 14 leads to the jacket spaces of chilling unit 5 and pipe 15 leads to the jacket spaces of chilling unit 10. Leaving unit 5 under control 20 of back pressure valve 16 and leaving unit 10 under control of back pressure valve 17 the cooling fluid is collected in cold fluid return line 18 and returned to expansion drum 11. Vaporized refrigerant from expansion drum 11 is drawn off under the control of back pressure valve 19, compressed by compressor 20, cooled in cooler 21, and returned to expansion drum 11 through compressed fluid return line 22 and pressure release valve 23. If found desirable, an additional pressure release valve 24 may be installed upon cold fluid return line 18 adjacent expansion drum 11 for a purpose later explained.

The operation of this system has the following 40 characteristics. The temperature of the fluid cooling medium in expansion drum 11 can be controlled by the inter-balance of the rate of pumping through pump 12, the back pressure held upon the vapors by back pressure valve 19, the rate of vapor withdrawal so controlled, and the degree of pressure drop through pressure release valve 23. Having an ample supply of cold fluid under pressure in the cold fluid header 13, an amount appropriate to the load being handled in any chiller unit, such as 5 may be withdrawn from that header and passed through the jackets of the chiller. Back pressure valve 16 on this unit 5, not only serves to control the amount so passed through the jackets of this chiller, but also holds it under sufficient pressure to prevent its evaporation as heat is withdrawn from the material being

chilled. It is to be understood that the speed of the pump is controlled manually, and the valves 16, 17 and 24 are adjusted manually from time to time, depending upon load conditions. Thus, if increased chilling is required, the pump 12 is speeded up, thus causing increased cooling in both of the units 5 and 10. If increased cooling is required in only one of said units the pump 12 is speeded and the back-pressure valve associated with the unit not requiring increased cooling is adjusted to raise the pressure therein. For example, if increased cooling is required only in the chilling unit 5, the back-pressure valve 17 is adjusted to increase the pressure in the chilling unit 10 and the pump 12 is speeded. As a result, increased cooling fluid passes through the chilling unit 5, while the flow of cooling fluid through the unit 10 remains substantially constant.

It is unnecessary to adjust the valves 19 and 23. Valve 23 is a pressure release valve which insures that the fluid back of the valve shall be maintained as a liquid while the fluid ahead of the valve coming into drum 11 is subjected to a reduced pressure which allows it to expand and evaporate. The back-pressure valve 19 is a differential pressure valve which insures that the pressure at the intake side of the compressor 20 is normally lower than that in the expansion drum 11, and also serves to prevent fluid from flowing from the compressor side of the valve back to the drum 11.

Automatic control could be devised to control the valves 16 and 17 and the pump 12 depending upon the temperatures in the chilling units 5 and 10 and the relation of these temperatures to each other. For example, if the temperature in either chilling unit increases above a certain predetermined maximum the pump 12 could be speeded. Alternatively, the speed of the pump could be controlled by the maximum temperature in either of the chilling units so that the higher the temperature in either of said units, the greater the speed of the pump and the lower the temperature the lower the speed of the pump. Also, a control could be devised for the back-pressure valves 16 and 17 so that the lower the temperature in either of said units, the higher the pressure should be adjusted for the valve controlling it. However, the automatic control of these valves and pumps is not a part of our invention and so need not be described in detail. Formerly, under gravity distribution, an increase in load of any slight proportion caused excessive vaporization in the jacket spaces, which cut down the heat transfer rate where vapor was present, increased the load upon remaining liquid covered heat transfer surfaces, caused vapor formation there, and so compounded the 'evil and effectively prevented the handling of heavier loading. With the present operation, increased loading merely calls for increased flow of cooling fluid, the increased flow of fluid is held by back pressure valve 16 under sufficient pressure to keep it liquid, and since increased liquid velocity gives higher heat transfer rate, the increased loading actually increases the efficiency of operation within reasonable limits.

The cooling fluid discharged from the jackets of each chilling unit goes to the cold fluid return line, which acts as a collecting manifold in case a number of units are used. In some cases, under these circumstances, the use of a back pressure valve, as at 24, upon the cold fluid return line, may be useful in securing uniformity of operation in this pipe.

Heat removed from the chilled material is dis-

charged into the expansion drum 11 by the cold fluid return and there is converted to latent heat of vaporization in refrigerant vapor, to be removed with that vapor and withdrawn from the system by cooler 21.

This system is, of course, applicable to any cooling system wherein a refrigerant medium is self cooled by partial vaporization and the remaining liquid circulated into indirect heat transfer relationship with the material to be cooled. While applicable to single cooling units it is most appropriate to systems where multiple cooling units operate in parallel from a single source of compressed refrigerant, giving to such systems a complete flexibility in the distribution of load among the several cooling units and permitting wide variations in the load which may be assumed by any unit without disturbing the operation of the other units. It does away with the provision of a separate expansion drum for each unit which has formerly been the only way of approaching independent adjustment of operation of an individual unit which is one of several operating from single source of compressed refrigerant.

The difference in pressure between the expansion drum and the cold fluid header, furnished by the cold fluid circulating pump need not be much greater than that required to overcome frictional resistance to liquid flow through the system. When properly operated, this pump does not need to furnish high pressure to overcome excessive vaporization in the chilling units. Even if so operated, however, the energy so expended can be recovered, in large part, by regulated pressure release from the cold fluid return line into the expansion drum, the vaporization attendant upon said release offering opportunity for such recovery.

We claim:

40. 1. In the operation of a refrigeration system wherein liquid refrigerant is self-cooled by partial evaporation and the remaining liquid is passed in heat exchange relationship with material to be cooled the method which comprises conducting partial evaporation in a vessel isolated from the material to be cooled, in which vessel a pool of cold liquid refrigerant is maintained and from which vessel vapors are withdrawn, to be compressed, liquefied, returned, and allowed to evaporate, and circulating cold liquid refrigerant from said pool to the material to be cooled and back to said pool while maintaining upon the liquid so circulated a pressure above that existing in the pool and sufficient to prevent substantial vaporization of the liquid refrigerant while it is being circulated from said pool to the material to be cooled and back to said pool.
45. 2. In the operation of a refrigeration system wherein liquid refrigerant is self-cooled by partial evaporation and the remaining liquid is passed in heat exchange relationship with material to be cooled the method which comprises conducting partial evaporation in a vessel isolated from the material to be cooled, in which vessel a pool of cold liquid refrigerant is maintained, and from which vessel vapors are withdrawn, to be compressed, liquefied, returned, and allowed to evaporate, delivering cold liquid refrigerant from said pool into a manifold pipe at a pressure above that existing in said pool, passing liquid refrigerant from said manifold in at least one stream in heat exchange relationship with material to be cooled and thence back to said pool, and maintaining upon said stream,
- 50.
- 55.
- 60.
- 65.
- 70.
- 75.

while in said heat exchange relationship, a pressure sufficiently elevated above that in said pool to prevent substantial evaporation of the liquid refrigerant while in said stream.

3. In the operation of a refrigeration system wherein liquid refrigerant is self-cooled by partial evaporation and the remaining liquid is passed in heat exchange relationship with material to be cooled the method which comprises conducting partial evaporation in a vessel isolated from the material to be cooled, in which vessel a pool of cold liquid refrigerant is maintained, and from which vessel vapors are withdrawn, to be compressed, liquefied, returned and allowed to evaporate, delivering cold liquid refrigerant from said pool into a manifold pipe at a pressure above that existing in said pool, passing liquid refrigerant from said manifold in a plurality of streams through cooling units wherein each stream is in heat exchange relationship with material to be cooled, returning said streams to said pool, and maintaining upon the liquid refrigerant while in said streams a pressure sufficiently elevated above that in said pool to prevent substantial vaporization of the liquid refrigerant while in said stream.

4. In a refrigeration system wherein liquid refrigerant is self-cooled by partial evaporation and the remaining liquid is passed in heat exchange relationship with material to be cooled the method which comprises conducting partial evaporation in a vessel isolated from the material to be cooled, in which vessel a pool of cold liquid refrigerant is maintained, and from which vessel vapors are withdrawn, to be compressed, liquefied, returned, and allowed to evaporate, delivering cold liquid refrigerant from said pool into a manifold pipe at a pressure above that existing in said pool, passing liquid refrigerant from said manifold in a plurality of streams through cooling units wherein each stream is in heat exchange relationship with material to be cooled, collecting the several streams together and returning them to said pool, controlling the quantity of each stream in response to the requirements of the material to be cooled, and maintaining upon the liquid refrigerant in each stream a pressure sufficiently elevated above that in said pool to prevent substantial vaporization of the liquid in said stream.

5. In a refrigerating system wherein a liquid refrigerant is self-cooled by partial evaporation and the remaining liquid is passed in heat exchange relationship with material to be cooled,

5 an expansion drum adapted to maintain a pool of cooled refrigerant, a vapor circuit comprising a back-pressure valve, a compressor, a cooler and a pressure release valve whereby vapors may be withdrawn from, compressed and liquefied, cooled and re-vaporized in said expansion drum, a pump for withdrawing liquid from said pool, a conduit whereby liquid from said pool may be passed in heat exchange relation with the material to be cooled and returned to said pool and a back pressure valve in said conduit between said material to be cooled and said pool.

10 6. In a refrigerating system wherein a liquid refrigerant is self-cooled by partial evaporation and the remaining liquid is passed in heat exchange relationship with material to be cooled, an expansion drum adapted to contain a pool of cooled refrigerant, a vapor circuit comprising a back-pressure valve, a compressor, a cooler and a pressure release valve whereby vapors may be withdrawn from, compressed, cooled and re-vaporized in said expansion drum, a pump for withdrawing liquid from said pool, a manifold into which liquid is discharged from said pump, conduits whereby separate streams of liquid may be led from said manifold, passed in heat exchange relation with the material to be cooled, and returned to said pool, and in each conduit a back pressure valve located between said material to be cooled and said pool.

15 7. In a refrigerating system wherein a liquid refrigerant is self-cooled by partial evaporation and the remaining liquid is passed in heat exchange relationship with material to be cooled, an expansion drum adapted to contain a pool of cooled refrigerant, a vapor circuit comprising a back-pressure valve, a compressor, a cooler and a pressure release valve whereby vapors may be withdrawn from, compressed, cooled and re-vaporized in said expansion drum, a pump for withdrawing liquid from said pool, a manifold into which liquid is discharged from said pump, conduits whereby separate streams of liquid may be led from said manifold, and passed in heat relation with the material to be cooled, a second manifold wherein said streams are re-collected and returned to said pool, in each conduit a back-pressure valve located between the material to be cooled and the re-collection manifold, 20 and a back-pressure valve between said re-collection manifold and said pool.
